UNITED STATES PATENT OFFICE.

FRANZ KRUCKENBERG AND CURT STEDEFELD, OF HEIDELBERG, GERMANY; SAID STEDEFELD ASSIGNOR TO SAID KRUCKENBERG.

TRACK FOR HIGH-SPEED SUSPENSION RAILWAYS.

Application filed January 24, 1925, Serial No. 4,568, and in Germany February 6, 1924.

The invention concerns a high speed suspension railway for suspension cars travelling with very great velocity about 200-300 M. P. H. on a single rail and particularly the 5 construction and arrangement of the permanent way for this railway. Further the invention is concerned with the details of the supporting means and also the construction works and steel work on which the 10 railsupports are fixed.

The rail itself must, in this invention be 15 protected against variations of temperature, for example housed in a tunnel or tube or constructed of a material which is in itself as far as possible indifferent to temperature changes, such as Invar whose expansion-coefficient for temperature is so small as to be practically negligible. Since all shocks 20 on the car must be avoided at this high speed the rail must have throughout its whole length an absolutely smooth surface and must be made of a material which will not rust and which is unaffected by atmospheric influences. Unevennesses or joint-spaces 25 which are present in the ordinary railway would at the great speed have a serious effect not only on the rail but also on the unsprung parts of the running-gears of the cars. Since small inequalities of the track 30 are in practice unavoidable the rail must be supported in an elastic manner and at the same time those portions of the track which must give beneath the weight of the car must be kept as light as possible; that is 35 the rail itself and the parts immediately adjacent which must give sufficiently quickly under the shock. Those unavoidably heavy parts such as the adjustment-arrangement 40 for the rail brackets may advantageously be transferred to points which give very little in the elastic movements of the system. The reason for this is that the inertia of an oscillating mass as is well known is dependent 45 on the product of the mass and the square of its velocity.

Since the jointless rail of temperature-indifferent material remains suspended without any appreciable expansion or contraction the girderwork being of ordinary material must be constructed in such a manner 50 as to be free to expand and contract independently of the rail. To this end are arranged in this invention supports which by hinging and bending allow the girder-work to expand independently of the rail 55

not only without introducing serious stresses but which are able to give vertically in an elastic manner.

Our invention is illustrated diagrammatically and by way of example in the accompanying drawings in which:

Fig. 1 (side elevation) and Fig. 2 (plan view) illustrate diagrammatically an example of a girder work system for supporting the rail of a high-speed suspension rail-way;

Figs. 3, 4, 5, illustrate rail-supports comprising supporting arms which make angular movement possible, by hinge-devices such as flexible plates;

Fig. 6 illustrates a modified form of rail-support;

Figs. 7, 8, 9 illustrate a rail-support comprising a bearer-arm formed from waved strip springs, thereby providing for vertical movement of the rail;

Figs. 10 and 11 are detail illustrations of the hinge devices shown in Fig. 9;

Fig. 12 illustrates another form of bearer-arm which like the one shown in Fig. 8 provides for vertical movement of the rail;

Fig. 13 illustrates an adjustable rail bracket;

Figs. 14 and 15 illustrate the method of adjusting the rails;

Fig. 16 is a tool, used for the above purpose;

Fig. 17 shows ferro-concrete girder work for high-speed suspension cars above a railway line;

Figs. 18 and 19 show iron girder works for high-speed suspension cars, respectively, beside and above railway lines;

Fig. 20 shows an arrangement where the rail is protected against injury due to variations in temperature;

Fig. 21 illustrates a construction wherein the entire track is protected against injury by wind or variations in temperature; and

Figs. 22 and 23 illustrate devices for protecting the cars against wind.

Fig. 1 shows in elevation and Fig. 2 in plan a diagrammatic example of the girder-work system for the supporting of the rail. Both rails 1 are fastened to the girderwork 2 by means of a triangulated projection consisting of the arms 3 and 4. At both ends of the arms 3 and 4 hinges 5 are introduced. The girderwork 2 is carried on columns 6 which rest on hinged bearings 8 on the 105 110

ground. Moreover the girderwork 2 rests on the sliding bearings 7 on the horizontal surface 6' of the columns 6. To transmit the horizontal forces from the rail 1 to the girderwork 2 the horizontal members 9 are provided. In consequence of this supporting of the rail on one fixed end of each separate girder-unit the lengthening of the latter gives the end of the supporting arms 3^a 4^a at the free end of the girder an equal movement. The other supporting arms not so distant from the fixed end experience a correspondingly smaller movement. In Fig. 2 the angular movements of the supporting arms are shown greatly exaggerated for purpose of explanation. In order to make possible these angular movements of the supporting arms 3 and 4 hinges 5 are provided (see Fig. 3), which in this invention can consist of flexible plates 5^a (see Fig. 4). The plates are positioned edgeways and vertically to the plane of the supporting arms 3 and 4. In contrast to normal hinges and sliding rail joints as in the normal railway in this manner is built a construction, which is remarkably solid and free from wear and chattering rail joints. Another form of support for a differently constructed girder-work 2 is shown in Fig. 5. The supporting arm 3^b is held by a vertical arm 4^b, which has introduced at its upper and lower ends virtual hinges. In consequence of the bending of the horizontal member, the rail is more elastically supported than in the triangular construction of Fig. 4. It is not impossible to suppose, that it might be preferable to support the rail even more elastically against strong vertical blows, as would be the case were the exact laying of the rail be found to be impossible from technical or economical reasons. In this case the rail supports can take up a very great amount of concussion energy. In Fig. 6 is utilized the elasticity of a beam or girder 3^c to which the rail is bolted. The beam is sufficiently elastic in the direction of the length of the rail to take up without further provision the relative movements between rail and girder-work due to temperature variations. The same end can be attained by means of springs. That these shall only come into action at a certain predetermined force of blow they are provided with preliminary tension. Two different arrangements of these elastic supports are shown in Figs. 5 to 11, the one in Figs. 5, 6 and 10, the other in Figs. 7 and 11. The rail 1 is fastened to the girderwork 2 by means of the supporting arms 3 and 4. The connections between them being made by means of the ball-joints 11, while the arm 4 is suspended at its upper end by means of the plate 5 which acts as a hinge. The bearer arm 4 is constructed as a spring by means of waved strips 12 (Fig. 8) which are joined together at the upper and lower ends and in the middle. The number of waves in these strips depends upon the amount of give required, the construction-material and the magnitude of the positive and negative axial forces. 70 The springs 12 can be preloaded by means of the restrainers 13, which may consist of brackets or bolts which prevent more than a predetermined bulging of the strips. At its lower end the bearer arm 4 is fastened to the bearer arm 3 by means of the plate 14 which acts as a hinge. If a vertical force sufficiently great to overcome the preload of the spring acts on the rail the waves of the strip-springs flatten out, lengthening the bearer-arm 4 and allowing the rail 1 together with the bearer-arm 3 to give downwards, the latter hinging on the ball-joint 11. This ball-joint must permit hinging in two planes, namely in the longitudinal direction of the rail because of temperature changes and also in a direction vertical to this. In addition it must be able to transmit the horizontal and vertical compressions and tensions due to the passing of the car and the force of the side-wind. Instead of the strip-springs other kinds can be used such as coil-springs in Fig. 12. The spring 24 is interposed between the piston 28 of the rod 27 and the housing 26 which is firmly bolted to the bearer-arm 3. 95 The screw-thread, by means of the nut 29 permits a preliminary load to be given to the spring and the tube 30, by being turned, can adjust the rail position to the desired height. The ball shaped washer 25 of the nut 29 permits a sufficient amount of hinging by means of the action of the spring and the side-play of the rod similarly to the case in Fig. 10 which may be explained as follows. In Fig. 10 is shown the construction of the ball-joints 11 to an enlarged scale. The hollow ball 15 on the arm 2^a of the girderwork 2 rests in the cup 16 on the bearer-arm 3 and is held in contact with it by means of the bolt 18 with head 19. The bolt 18 has play 100 in the hollow ball 16 so that small movements of the axis of the bolt can allow for the small vertical and horizontal movements of the bearer-arm. The pressure of the spring prevents chatter. The arrangement of ball-joints is shown replaced in Figs. 7 and 11 by two plates mutually at right angles. The hinging of the arm 3 in a vertical plane is provided for by the plate 21 between the girderwork 2 and the supporting arm 3, while the vertical plate 22 provides for the horizontal hinging of the bearer-arm 3. Supposing the arm 3 were made of two angle-irons 23 riveted together instead of the special plates the horizontal flanges could be cut away to a required extent as Fig. 11 shows. At the beginning it was stated that the mass of the parts subjected to shock must be as small as possible; this includes the rail and bearer-arms. The 115 120 125 130

greater the distance apart of the bearer-arms, the greater must be the weight of the rail and vice-versa. Therefore there must be in this construction one particular arrangement which is the most favorable. To this end one may reduce the weight of the bearer-arm of Fig. 6 by making it of such a section as to have a constant bending-resistance the section in consequence varying in proportion to the length. In this way its mass-center approaches still nearer to the supporting girder-work so that the mass to be moved is reduced still further. A further reduction of the mass of the bearer-arm can be effected by using material with a very high elastic-limit so that it can give very considerably without being permanently distorted.

The rail 1 must be so fastened to the girderwork, that it lies absolutely in straight lines or smooth curves. Because the rail must be mounted on the previously constructed girderwork the bearer-arms interposed must be such as to permit the exact alignment of the rail. A similar alignment is necessary at the curves and in the transition from the straight track. In order that in such a transition no violent increase of centrifugal force of the car shall take place at the high speed the curves must be made according to certain definite laws and be laid quite smoothly. For this purpose in this invention an arrangement (see Figs. 13 to 16) is provided which makes possible the exact alignment of the rail both vertically and horizontally. On the gussetplate 31 (see Fig. 13), which is fastened to the bearer-arm is arranged the rail-bracket 32 in a manner that it is vertically adjustable while for horizontal adjustment the side plates 33 are provided. In either movable part namely the rail-bracket 32 and the side-plates 33 the usual boltholes are replaced by larger oval slots 37 and 37^a, respectively, in which engage projections of the plates 38 and 38^a respectively. The latter are, in the regions of the projections, provided with holes 35 and 35^a in which the fastening bolts fit very exactly. The series of locking plates with the bolt-holes drilled in different positions is stocked in a systematic assortment. In fitting the rail-holders 32 those locking-plates are chosen in which the holes 35 and 35^a correspond exactly with the holes 38 and 38^a in the gusset-plates 31 when the rail has been correctly aligned. Thus by the locking-plates and in particular the arrangement of the holes drilled in them any desired adjustment of the rail 1 relative to the girderwork can be obtained. When the locking-plates with their projections are engaged in the slots in the rail-holders and the bolts are passed through the holes and bolted up, the adjustment of the rail is rendered permanent. Of

course the function of the oval slots and projections can be performed in other ways such as circular projections and eccentrically drilled bolt-holes. For the finest adjustments of the rail a special arrangement shown in Fig. 14 is provided resembling a pair of dividers the operation of which is carried out in conjunction with an optical arrangement shown in Figs. 15 and 16. On the rail 1 is fixed a telescope 43 and at a distance away a cross hair 44. The adjustment of the rail on the holder is performed as follows. Two pairs of dividers as shown in Fig. 14 fit with their wingnut-ends 39 in the holes 34 of the fixed part of the holder 80 while the ball-ends 40 engage with the holes 36 in the corresponding movable parts of the holder (rail-bracket and side plates). By turning the screw spindle 42 by means of the hand-wheel 41 the movements of the rail-holder parts can be carried out very exactly. For the alignment the optical arrangement is employed until the desired position is attained. On the dividers may be mounted a scale for reading off the movement given. When the adjustment of the various parts has been concluded by means of a gauge or similar device, the appropriate locking-plates are selected from the series having bolt-holes, the distance apart of which is appropriate to the particular case. These plates 38 will be bolted up with their projections engaging in the spaces 37. For the easier selection of the appropriate plate they will be stamped with indicating marks and so formed that one set of plates can be used for both adjustments. Naturally the two separate adjustments can be provided for at different positions on the bearer-arms. For instance the horizontal adjustment can be made by means of the rail-bracket at the end of the bearer-arms and the vertical adjustment provided for at the point where the supporting arms join the girderwork. A decisive factor in this question is as before explained the distribution of the sprung-masses.

The constructions supporting the rail must be shaped to conform with the circumstances of any particular case. If an existing railway, canal or road be used in order to save earthwork and transport-costs the construction for carrying the quick-railway must have a profile such as to allow the particular traffic to pass freely. They consist then of girders carried on posts or arches (see sections Figs. 17-23). In the arrangement of this girderwork is taken into consideration that inspection and repair-work must be carried out on the track and consequently platforms 47 (see Figs. 18, 20, 22, and 23) are provided and in addition a track 46 (see Figs. 17-22) along which repair-cars 45 can travel. Also the repair-cars shown in Figs. 17 to 19 and 21 and 22 can

- be used to draw a broken-down high-speed-car to a repair-depot. In the ferro-concrete girderwork shown in Fig. 17, the quick-railway cars 48 are running on the rail 1 above a double-track normal railway 49, while above and between them are arranged rails 46 on which run the repair-cars 45. In the construction shown in Fig. 18 on either side of the supporting pillars are the rails 1, 10, while on the top of the rectangular girder-work is the track 46 for the cars 45. In the construction in Fig. 19 from the steel-girders are suspended two repair-cars 50 outside the rails 1 running on two single rails 46a. The post shown in Fig. 20 carries a girderwork of rectangular section through which spaces are provided for the repair-cars to pass. The question as to which of the methods of track-construction shown in Figs. 17-23 must be employed depends as has been said upon the condition of the ground and whether already existing ways can be used. This depends upon whether an already existing railway-line is suited to the requirements of the quick-railway. Because of the high speed the course of the track must be laid in accordance with certain definite laws. In order to protect the rail against the undesirable influence of the atmosphere including snow, rain, ice and so on, it can if desired be provided with a covering. By building the rail in through-bridges or tunnels (see Figs. 17, 21) no further weather protection is necessary. In the case of the girderworks in the Figs. 19 and 20 a roof 51 can be provided for protecting the rail 1. These roofs at the same time also protect the girders. They do not interfere with the towing of a disabled suspension car by the repair-cars. In the construction shown in Fig. 20 the roof can be extended along the whole girderwork, whereby not only this but also the repair-cars and their rails are protected from the weather.
- If it is wished to protect the car against the bad effects of side wind in practice a wind shield may be provided along the girderwork so that the car travels protected by it (Figs. 21-23). As shown in Fig. 21, which corresponds to Fig. 17, the car travels between two shields 52, that are constructed e. g. of corrugated iron or sheet iron. At the same time the whole interior by means of this roof 51 is protected from rain and snow. In Fig. 22 the car runs outside the windshields 52, but so close that the force of the wind on either side of the car is practically the same. In Fig. 23, which shows only one half of the girderwork system, the windshield 53 stops only the lower part of the airstream, while the upper part above and below the rail 1 applies equal and opposite moments about the rail on the car, which effect must be ensured by making the shield 53 of the right height so that the car 65 remains in its normal vertical position.
- What I claim is:
1. A track for high-speed suspension-railway of the kind described, comprising, in combination, a structure adapted to support the line of rails in elevated position rail-bearing arms projecting forth from said structure, and a line of rails carried by said arms in a position parallel to said supporting structure, the said arms being provided with means for permitting automatic shifting of the line of rails relatively to the supporting structure, substantially as set forth. 75
  2. A track for high-speed suspension-railway of the kind described, comprising, in combination, a structure adapted to support the line of rails in elevated position rail-bearing arms projecting forth from said structure, and a line of rails carried by said arms, these latter and the said arms being provided with means for permitting automatic shifting of these parts relatively to one another, and said line of rails having a continuous smooth running surface or tread, substantially as set forth. 90
  3. In combination, a superstructure, brackets projecting laterally therefrom, yielding joints between said brackets and said superstructure, and rails secured to the said brackets. 95
  4. In combination, a superstructure, brackets constructed as triangulated bonds and projecting forth laterally from said superstructure, yielding joints between the brackets and the superstructure and at the free ends of the brackets, and rails secured to the brackets by means of the last mentioned yielding joints. 100
  5. In combination, a superstructure, brackets projecting laterally therefrom, yielding joints consisting of members of bendable sheet metal connecting said superstructure and the brackets with one another, and rails secured to the said brackets. 105
  6. In combination, a superstructure, elastic brackets projecting laterally therefrom, yielding joints between said brackets and said superstructure, and rails secured to the said brackets. 110
  7. In combination, a superstructure, elastic brackets projecting laterally therefrom and so constructed and arranged as to have a preliminary tension determined in relation to the normal load, yielding joints between said brackets and said superstructure, and rails secured to said brackets. 115
  8. In combination, a superstructure, brackets having an elastic member comprising bulged out flat springs projecting laterally from the superstructure, said springs being arranged in pairs with the bulged out portions located opposite one another, members connecting said bulged out portions of the 120
  9. In combination, a superstructure, brackets having an elastic member comprising bulged out flat springs projecting laterally from the superstructure, said springs being arranged in pairs with the bulged out portions located opposite one another, members connecting said bulged out portions of the 125

springs with one another, and rails secured to the free ends of the said brackets.

9. In combination, a superstructure, elastic brackets formed by bulged out flat springs projecting laterally from said superstructure, said springs being arranged in pairs with the bulged out portions located opposite one another, members connecting said bulged out portions of the springs with one another, and rails secured to the free ends of said brackets.
10. In combination, a superstructure, brackets projecting laterally therefrom, yielding joints between said brackets and said superstructure, rails secured to the brackets, and rail adjusting devices attached to said brackets and constructed and arranged for horizontal and vertical adjustment to permit corresponding adjustment of the rails.
11. In combination, a superstructure, brackets projecting laterally therefrom, yielding joints between said brackets and said superstructure, rails secured to the brackets, rail fastening means and rail supporting means, said fastening means constructed and arranged for vertical movement in said supporting means, and means for securing said fastening means in adjusted position, said supporting means constructed and arranged for horizontal movement relative to the bracket and means for securing said means in adjusted position.
12. In combination, a superstructure, brackets projecting laterally therefrom, yielding joints between said brackets and said superstructure, rails secured to the brackets, rail fastening means and rail supporting means, said fastening means constructed and arranged for vertical movement in said supporting means, means for securing

- said fastening means in adjusted position, means for permitting shifting of the brackets relative to the superstructure, and means for securing the brackets in adjusted position.
13. In combination, a superstructure, brackets projecting laterally therefrom, yielding joints between said brackets and said superstructure, rails secured to the brackets, rail fastening means and rail supporting means, means permitting shifting of said fastening means vertically in said supporting means, and means for securing the fastening means in adjusted position, means for adjusting the rails horizontally, said rails having recesses, members having lugs adapted to engage said recesses and bolts connecting said members and the rails.
14. In combination, a superstructure, brackets projecting laterally therefrom, yielding joints between said brackets and said superstructure, rails secured to the brackets, rail fastening means and rail supporting means, said fastening means being constructed and arranged to be shifted vertically in said supporting means, and means for securing said fastening means in adjusted position, means for adjusting the rails horizontally, adjustable plates having lugs adapted to engage correspondingly located recesses in the rail-holders, said plates having sets of holes provided at different parts and arranged for horizontal as well as for vertical adjustment of the rails, fastening bolts, the bolts and holes being provided with marks.
